UNITED STATES PATENT OFFICE

CLIFFORD A. FOGEL AND FRED O. NELSON, OF PITTSBURGH, PENNSYLVANIA

MERCHANTISE DISPLAY HOLDER

Application filed November 23, 1929. Serial No. 409,372.

Our invention relates to certain new and useful improvements in merchandise display holders somewhat of the type disclosed in our co-pending application for Letters Patent of the United States, bearing filing date the 14th day of August, 1929, and Serial No. 385,830.

The primary object of this invention is to provide a more substantial and efficient holder which will cost comparatively less to manufacture, assemble and install.

Further objects of the invention are to provide a device of the character described, which is adapted to being attached to ordinary store shelving for supporting a pair of superposed containers, one of the latter being transparent and containing and displaying specimens of a product identical to that contained in the other container of conventional sales construction, and of the kind stored in the shelving equipped therewith; which is simple in construction and arrangement, durable, efficient in its use, and attractive in appearance; which embodies relatively few parts; and which does not project forwardly from the associated shelving, whereby the same does not require additional space, nor inconvenience the handling of merchandise on shelving equipped therewith.

To the accomplishment of these and such other objects as may hereinafter appear, the invention consists of the novel construction, combination and arrangement of parts herein specifically described and illustrated in the accompanying drawings but it is to be understood that changes in the form, proportions and details of construction may be resorted to that come within the scope of the claims hereunto appended.

In the drawings, wherein like numerals of reference designate corresponding parts throughout the several views:—

Figure 1 is a side elevational view of a merchandise display holder, constructed in accordance with the invention, and illustrating its adaptation with a shelf and display containers.

Figures 2 and 3 are plan views of the

blanks from which the retaining band and support therefor are, respectively, formed.

Figure 4 is a fragmentary inner side view illustrating the connection of the retaining band with its support. 55

Figure 5 is an enlarged sectional view on line 5—5, Figure 4.

Figure 6 is a bottom plan view of the support.

Referring in detail to the drawings 1 and 2, respectively, denote a retaining band and a support for the latter. The retaining band 1 and the support 2 are constructed from any suitable sheet material, preferably sheet metal. 60

The support 2 is concavo-convex in transverse cross section, and has its lower end formed with a plurality of forwardly projecting, apertured ears 3, which are adapted for engagement by nails 4, or any other suitable attaching elements, for fixedly and permanently securing the support 2, in the vertical position, to a shelf 5, at the forward edge margin of the latter. 70

The top of the support 2 is provided with a pair of connecting lugs 6, which are disposed at respective ends thereof. Each of the lugs 6 is associated with a rectangularly shaped notch 7. The latter are formed in the top of the support 2 and have their outer side walls aligned with the inner side edges of respective connecting lugs 6. The connecting lugs 6 extend vertically and are longitudinally aligned with the support 2. 75

The top of the support 2 is further provided with a vertically extending and integrally formed retaining lug 8, which is disposed centrally intermediate of the connecting lugs 6, for the purpose hereinafter set forth. 85

The retaining band 1 is carried at and projects forwardly from the top of the support 2, and is disposed at right angles relatively to the latter. Each end of the retaining band 1 is provided with an inwardly disposed, horizontally disposed loop 9, which is preferably stamped therefrom and adapted for the passage and engagement of respective connecting lugs 6, of the support 2. The connection of the retaining band, 95

100

with the support 2, is clearly illustrated in Figures 1 and 2.

It will be noted that when these parts are assembled, in the manner stated, the upper ends of the connecting lugs 6 are bent slightly outwardly, as at 10, for rigidly securing the retaining band 1 in its assembled position with the support 2. The rearward ends of the loops 9 engage in respective notches 7 and such engagement materially aids in establishing a more rigid connection between the retaining band 1 and its support 2.

When assembled together, the retaining band 1 and the support 2, combinedly constitute a circular holder, which surrounds and embraces the adjoining ends of the upper transparent display container 12 and the lower regulation container 13. It will be evident, that while the display container 12 is preferably disposed above the regulation container 13, their relative positions may be reversed, if desired. Further, the regulation container 13 may either be constructed from opaque or transparent material so long as it conforms to the regulation containers stored on the associated shelf.

The lower edge of the retaining band 1 is formed with a plurality of integrally formed seating lips 11, which are suitably spaced from each other and shaped by bending the same upwardly and inwardly against the inner face of the retaining band 1, as clearly shown in Figures 4 and 5. The seating lips 11 are adapted to engage the bottom of the upper display container 12 for supporting the latter and for engaging the top of the lower regulation container 13 for maintaining the latter in position on the shelf 5 against the concaved forward face of the support 2. The upper display container 12 is further secured against movement by forcing the retaining lug 8 forwardly against same, as illustrated in Figure 1. By resting the lips 11 upon the top of the lower regulation container 13, the latter will assist in supporting the upper display container 12, and prevent the possible sagging of the retaining band 1 from the weight of the display container supported thereby.

A small upturned hook member 14 is formed integral with the forward lower edge of the retaining band 1. The hook member 14 is adapted for the attachment or suspension of price cards, and the like, appertaining to the goods displayed by the device. In storing canned goods on store shelving, usually two tiers of cans are placed on the same shelf. The feature of the present invention resides in the provision of a holder for supporting a pair of superposed containers, one of which is transparent and filled with a product of the kind, trademarked brand, and quality contained in the

regulation can or container 13, the latter being a unit of and identical to the canned product stored on the shelf equipped with the device. The purpose of so displaying the merchandise being, of course, to stimulate the sale thereof.

The curvature of the support 2 is approximately conformed to the curvature of the cylindrical containers supported thereby and is considerably less than semi-cylindrical, so that no part of the support 2 is visible when the containers are viewed from the front thereof.

The improved holders are preferably positioned centrally of the shelves 5 and so disposed that no part thereof projects beyond the forward edge of the shelves equipped therewith. In consequence, the same will not require any special attaching elements, nor require additional space, nor interfere with the handling of the canned goods upon the shelves. It is, of course, obvious that the holder may be secured on a counter or other structure than shelving to display the goods carried by or surrounding same.

It will be noted that our improved holder comprises but two parts, which may be cheaply stamped, formed and assembled, and which may be readily taken apart and stacked, thereby facilitating its transportation and storage.

The present invention provides a most efficient and inexpensive device of its kind for supporting, maintaining and displaying merchandise of the class stated.

What we claim is:

1. A merchandise display holder of the character described comprising a vertically disposed support, means for securing said support in position, a retaining band having its ends detachably connected to the top of said support and being disposed horizontally and inwardly extending seating elements formed integral with said retaining band.

2. A merchandise display holder of the character described comprising a vertically disposed support, means for securing said support in position, a retaining band having its ends detachably connected to the top of said support and being disposed horizontally, inwardly extending seating elements formed integral with said retaining band, said support being concavo-convex in transverse cross section, and a retaining lug disposed centrally of and formed integral with the top of said support.

3. In combination, a merchandise display holder of the character described comprising a support being concavo-convex in transverse cross section, means for securing said support in the vertical position, a pair of vertically extending connecting lugs formed integral with the top of said support, said support being provided with a pair of notches associated with respective connecting

lugs, a retaining band, a loop formed at each end of said retaining band and being adapted for engaging respective connecting lugs and in said notches for securing said connecting bands to said support, and inwardly extending seating elements formed integral with said retaining band.

4. In combination, a merchandise display holder of the character described comprising
10 a support being concavo-convex in transverse cross section, means for securing said support in the vertical position, a pair of vertically extending connecting lugs formed integral with the top of said support, said
15 support being provided with a pair of notches associated with respective connecting lugs, a retaining band, a loop formed at each end of said retaining band and being adapted for engaging respective connecting
20 lugs and in said notches for securing said connecting band to said support, inwardly extending seating elements formed integral with said retaining band, and a retaining lug disposed centrally of and formed integral
25 with the top of said support.

In testimony whereof we affix our signatures.

CLIFFORD A. FOGEL.
FRED O. NELSON.
